ROTARY PUMP, COMPRESSOR, OR THE LIKE

Miller R. Hutchison, Jr., Madison, N. J., assignor
to Multicycol Pump & Engine Corporation,
New York, N. Y., a corporation of New York

Application November 30, 1932, Serial No. 644,995

6 Claims. (Cl. 103—122)

The objects of the present invention are to attain in machines of the nature of rotary pumps, compressors, and the like, greater useful displacement than has been possible in machines of prior design and with minimum friction losses and with few simple parts of practical sturdy design.

The foregoing and other desirable objects are attained in the constructions hereinafter described, by the novel features of construction, combinations and relations of parts disclosed and broadly covered in the claims.

The drawings accompanying and forming part of the specification illustrate different practical embodiments of the invention, but as the same are primarily for purposes of disclosure, it will be understood that the structure may be modified and changed in various ways, all within the true spirit and broad scope of the invention.

Figs. 1 and 2 are vertical sectional views of one simple form of the invention, Fig. 1 being taken as on the plane of line 1—1 of Fig. 2 and Fig. 2 being taken as on substantially the plane of line 2—2 of Fig. 1.

Figs. 3 and 4 are similar views of another embodiment involving additional valving features, Fig. 3 appearing as on line 3—3 of Fig. 4 and Fig. 4 appearing substantially as on line 4—4 of Fig. 3.

In the form of the invention as first illustrated, a series of variable displacement chambers 5 are provided between hollow faced rockers 6, and a contacting flexible belt or band 7, which is given an undulatory action by an internal set of rollers 8, journaled at 9, on the arms of a spider structure 10, carried by a shaft 11. These rockers as shown in both views, have flanges or lips 12, slidingly engaging over the edges of the belt to serve as end closures for the crescent-shaped displacement chambers formed between the belt and the concave faces of the rockers.

The concave faces of the rockers may be formed as shown at the top in Fig. 1, on arcs 13, struck from the roll centers 14, to closely fit the belt as the rolls come into the radially aligned positions with the rockers, thus reducing the clearance volume to a minimum, but if desired, this curvature may be less or greater than a true arc from the roll centers. The forward and trailing edges of the rockers may be rounded as indicated at 15, to enable them to follow smoothly and fit closely the face of the belt or ribbon.

The rockers may be mounted in various ways

and in the illustration, they are shown as having rounded hub portions 16, backed by resilient pads or cushions 17, in substantially semi-circular seats 18, in the casing or surrounding frame 19 of the machine. Flanges or lips 20 at the inner edges of the semi-circular seats hold the resilient supporting pads in place and, if they are made to fit the rounded hub portions of the rockers as shown, they may be utilized also as guides or gages for the rocker movements, preventing also the drag of the belt from bodily displacing the rockers.

The hub portions of the rockers are shown as hollow at 21, to form fluid passages and as having slots or ports 22, opening inward through 70 the concave chamber walls of the rockers.

Suitable fluid conducting connections are made with the hubs of the rockers. In Fig. 2, this is shown effected by pipe connections 23, 24, at the ends of the casing in line with the passages or bores 21, in the hubs of the rockers, said piping including, in the case of the pump construction for instance, suitable intake and exhaust valves 25, 26, which may be simply properly arranged check valves in these pipe connections. The connections to and from the several rockers may be suitably manifolded in or as portions of the casing, or by separate piping outside the casing and, in the case of such manifolding, only one intake and one exhaust valve need be used, instead of separate valves for each rocker chamber, if the number of rockers and rollers be equal.

In Figs. 3 and 4, a variation of the invention is illustrated, wherein the variable displacement chambers are formed by the cooperation of the undulating ribbon 7', with the surrounding cylindrical wall 27 of the casing and slides 28. The latter are shown as having rocking seals 29, engaging the ribbon face, but inasmuch as there need be no relative sliding movement between the ribbon and slides, said slides may be attached to and form in effect, integral projections of the ribbon, said projections operating in the boxes 30, in the same way that the parts 28 operate therein, though possibly they need not be backed up by springs 31, like the slides 28.

The valving of the pump chambers is effected, in the case shown, by providing the intake and exhaust passages 32, 33, in the casing at opposite 105 sides of the slides and by constructing the slides with valve lips 34, 35, at their inner ends co-operable with valve seats 36, 37, to close the ports as the undulations pass beneath the slides, preventing communication between adjoining cham- 110

bers. The ports 32, 33 are shown in Fig. 3 as having manifolding connections 38.

In this second form of the invention, the rollers lay the belt upon the cylinder wall as an end-
5 less track and without sliding movement as be-
tween the outer surface of the belt and the wall.
In this fashion, the segmental shaped chambers
are in effect translated about the axis of the shaft
through undulation of the belt and providing
10 relatively large displacement within the physical
dimensions of the machine. Because the belt is
not so long as the periphery of the cylinder, it
will retreat in one revolution, a distance approxi-
15 mately equal to the difference in the length of
the belt and the periphery of the cylinder. This
retreat or creep is not objectionable, the motion
being relatively slight.

In both forms, the wear on the belt is com-
paratively light. The belt however is readily re-
20 placeable.

Different materials may be used for the belt,
such as rubber, fabric reinforced rubber, or a re-
silient material, such as rubber, with a suitable
25 backing of flexible metallic tape. The belt may
be in single or multiple layers. The end closures
engaging the edges of the belt may be appropri-
ately shaped to best make sealing engagement
30 with the lightest friction. For example, in the
second form, the end faces of the casing may be
somewhat coned toward the center to compen-
35 sate for any attenuation of the belt between ad-
joining rollers. Also, the rollers may be ten-
sioned outwardly to compensate or take up for
wear or stretch of the belt. This effect is ac-
complished in the second form of the invention
40 by the follower springs in back of the gates or
slides which ride the surface of the belt.

In the second form of the invention, the several
45 intake and exhaust passages may be severally
branched to suitable main in and out passages
on or connected with the casing of the so-called
roller-ribbon pump, engine, compressor or the
like.

As an aid to maintaining proper sealing en-
45 gagement between the ribbon and the companion
chamber forming member or members, pressure
may be introduced in back of the ribbon, that is,
inside the roller assembly. In the first form of
50 the invention, such pressure against the inside
of the belt may be opposed by pressure over the
rockers, holding the latter against the outside
face of the belt. If the casing is made fluid tight
55 with space about and over the rockers, such as
indicated at 39, Fig. 1, the opposing pressure
mentioned may be introduced in any convenient
way to the interior of the casing. If the inside
60 and outside pressures are to be equal, the space
inside the belt may be in free communication with
the outer space 39 of the casing. If however,
these pressures are to be different, the inside
65 space of necessity is separated from the outer
casing space, as by endwise abutment of the belt
and rockers with the end walls of the casing, sub-
stantially as indicated at 40 in Fig. 4. Pressure
applied externally to the rockers, opposing pres-
70 sure in the chambers 5, eases the bearing loads of
the rockers in their journals in the casing. By a
proper selection of these pressures, leakage from
and or into chambers 5 may be controlled. In
the first form of the invention, it will be noted
75 that the arrangement of parts is such, that the
pressure developed in the chambers 5 never op-
erates at any time to influence the turning of
the rockers about their own axes. As a conse-
quence, the only force which is required to oscil-

late the rockers is that sufficient to overcome the
moment of inertia of the rockers and friction in
the bearings, the pressure having no torque in-
fluence. The belt may be anchored against
creeping in the cylinder, in the second form of the
invention, as heretofore described, by means of
80 integrally connected slides, operating in the cas-
ing, if it be made of approximately the same
length as the inside circumference of the cylin-
der. If desired, stretch and wear of the belt may
be compensated for by a suitable follower or fol-
85 lowers, yieldingly engaged with one or both edges
of the belt, backed up by spring or fluid pressure.
From the foregoing, it will be apparent that
many changes may be made in the structure with-
90 out departure from the true spirit and broad
scope of the invention.

What is claimed is:

1. A machine of the character disclosed, com-
prising in combination, a casing and a shaft rela-
tively rotatable, said casing having concave
chamber defining walls therein substantially con-
centric to the shaft, three or more rollers con-
centrically grouped on the shaft and an endless
95 belt located entirely within the casing extending
about said three or more rollers and co-acting
with said chamber forming walls within the cas-
ing to form therewith variable displacement
chambers in the relative rotation of the shaft
and casing, the chamber forming walls within
100 the casing including a plurality of hollow rock-
ers having sealing engagement with said belt and
means for valving the confined spaces between
said hollow rockers and endless belt.

2. A machine of the character disclosed, com-
prising in combination, a casing and a shaft
relatively rotatable, said casing having concave
chamber defining walls therein substantially con-
centric to the shaft, three or more rollers con-
centrically grouped on the shaft, an endless belt
110 located entirely within the casing extending
about said three or more rollers and co-acting
with said chamber forming walls within the cas-
ing, to form therewith variable displacement
chambers in the relative rotation of the shaft
115 and casing, the chamber forming walls within
the casing including hollow rockers having seal-
ing engagement with said belt and provided with
valved intake and exhaust ports controlling flow
to and from the confined spaces between said
120 hollow rockers and endless belt.

3. A machine of the character disclosed, com-
prising in combination, a casing and a shaft rela-
tively rotatable, said casing having concave
chamber defining walls therein substantially con-
centric to the shaft, three or more rollers con-
centrically grouped on the shaft, an endless belt
130 located entirely within the casing extending
about said three or more rollers and co-acting
with said chamber forming walls within the cas-
ing to form therewith variable displacement
chambers in the relative rotation of the shaft
135 and casing, said chamber forming walls within
the casing including a circular chamber wall
surrounding the belt and gates extending inward
from said surrounding wall to said belt and mov-
able to follow the undulatory action of the belt.

4. A machine of the character disclosed, com-
prising in combination, a casing and a shaft
relatively rotatable, said casing having concave
chamber defining walls therein substantially con-
centric to the shaft, three or more rollers con-
centrically grouped on the shaft, an endless belt
145 located entirely within the casing extending
about said three or more rollers and co-acting

with said chamber forming walls within the casing to form therewith variable displacement chambers in the relative rotation of the shaft and casing and gate members extending outward from the belt and mounted to follow the undulatory movement of the belt.

5. A machine of the character disclosed, comprising in combination, a concaved faced rocker, a roller mounted for travel in a path across the hollow face of the rocker and a strip of flexible sealing material interposed between the roller and hollow face of the rocker, said rocker having end flanges in sealing engagement over the edges of said flexible strip.

15

6. A machine of the character disclosed, comprising in combination, a casing, a shaft operating therein, said casing having a chamber wall concentric to the shaft axis, rollers carried by said shaft, an endless belt extending about said rollers and adapted to be carried thereby in undulatory fashion in engagement with said surrounding chamber wall and chamber defining gates slidingly mounted in the casing and co-operating with the undulatory belt.
